UNITED STATES PATENT OFFICE.

WILLIAM ROBERT BOHMERT, OF LARCHMONT, NEW YORK.

BILLING DEVICE.

No. 860,439.

Specification of Letters Patent.

Patented July 16, 1907.

Application filed May 2, 1907. Serial No. 371,417

To all whom it may concern:

Be it known that I, WILLIAM ROBERT BOHMERT, a citizen of the United States, and a resident of Larchmont, in the county of Westchester and State of New York, have invented a new and Improved Billing Device, of which the following is a full, clear, and exact description.

This invention relates to certain improvements in billing devices, and more particularly to means for holding a bill and the sales sheet or loose leaf of a sales book while the bill is being made out and, at the same time, copied upon the sales sheet or leaf of the sales book by means of suitable transfer paper.

In my improved device each bill may be made to closely follow the preceding one irrespective of the length of the latter, whereby all of the space upon the sales sheet may be utilized. The sales sheet is firmly held upon a suitable support while the bill is mounted at its right-hand end upon a sliding carrier, the left-hand end of the bill being steadied by the fingers of the left hand, thus preventing the bill from becoming displaced while it is being written. The carbon sheet is secured to the carrier and moves therewith, thus permitting of the use of a carbon sheet of the minimum size, and obviating the necessity for touching the carbon sheet with the fingers during the filling of an entire sales sheet. The carrier is so constructed that it is held in place by mere frictional engagement with its slideway, thus eliminating all catches or fasteners, but, at the same time, providing against accidental displacement. The board or main support is provided with a scale adjacent the bill carrier, whereby the point at which one bill ends may be noted on the scale, and the next bill may be begun at this point without raising the carbon sheet and inspecting the sales sheet.

The invention consists in certain features of construction and combination of parts, all of which will be fully set forth hereinafter and particularly pointed out in the claims.

Reference is to be had to the accompanying drawings, forming a part of this specification, in which similar characters of reference indicate corresponding parts in all the figures, and in which

Figure 1 is a plan view of my improved device illustrating the manner of securing the bill and the sales sheet thereto; Fig. 2 is a transverse section on the line 2-2 of Fig. 1; and Fig. 3 is a plan view of the bill and carbon sheet carrier.

In the preferred form of my improved device, I employ a suitable board or support 10 rectangular in form and constructed of any suitable material which will not readily crack, split, or warp. The board is constructed as thin and as light as possible to give the required strength, and the back of the board may be pro-

vided with rubber legs or projections 11, whereby the device may be supported upon a table top without liability of scratching or marring the latter. The support is provided with means for securely holding a sales sheet or the loose sheet of a sales book thereon, and provided with a sliding carrier to which the carbon sheet and the bill are attached.

To more fully set forth the working of my improved device, I have illustrated the same as having a loose leaf 12 of a sales book attached thereto. The support is provided with a plurality of pins or studs 13 adjacent the left-hand side thereof and adapted to enter the openings in the sheet by which the said sheet is secured within the sales book. The sheet is provided with a detachable strip 14 at the opposite edge thereof, which strip is also provided with openings 15 by which the sheet may be secured upon the studs or pins 13 when the opposite side of the sheet is being employed. The sheet is first filled in the position illustrated in the drawings, and then is reversed and the openings 15 placed over the pins 13 and the opposite side of the sheet filled. The strip 14 may then be torn off along the line of perforations 16 and the sheet secured in the sales book.

Adjacent the right-hand edge of the support, I provide a groove adapted to receive a sliding carrier 17. The carrier preferably comprises a single strip of metal slightly curved longitudinally and having a plurality of studs or pins 18 to which the bills and carbon paper may be secured. For guiding the carrier the side of the support is provided with a groove extending from the top to the bottom and having a sheet metal guideway 19 secured therein. The guideway is provided with inwardly directed flanges 20 which engage with the upper surface of the carrier 17 and hold the latter against lateral or vertical movement. The carrier may fit as snugly as desired beneath the flanges 20, but preferably the carrier is slightly thinner than the space beneath the flanges and the slight curvature of the carrier causes a firm frictional engagement, although permitting of a free longitudinal movement of the carrier upon the application of a slight pressure thereto. The bills 21 are provided with a detachable stub portion 22 having openings therein for the reception of the studs or pins 18 of the carrier, and are so ruled as to agree with the ruling of the sales sheet or leaf of the sales book. A sheet of carbon paper 23 is provided of substantially the same size as the bills, and is also provided with perforations for the reception of the studs 18, whereby the bill and carbon sheet may be moved longitudinally of the sales sheet by moving the carrier along its slideway. Adjacent the slideway the support is provided with a suitable scale 24 which may consist of numbers or other suitable

2

characters printed directly upon the support or printed upon a plate rigidly secured thereto. The stub portion of the bill is provided with a line or arrow 25 in alinement with the first line of the heading of the bill 5 and terminating adjacent the scale, as is clearly indicated in Fig. 1, to represent the starting line of the bill, and the lines of the body of the bill extend across the stub terminating adjacent the scale, so as to indicate thereon the last line of the particular bill being written.

10 In the use of my improved device, the loose leaf of the sales book, the carbon paper and the bill are assembled in the manner indicated in the drawings. The carrier is moved until the starting line 25 points to the zero of the scale and the left-hand edge of the 15 bill is firmly held in place by the fingers of the left hand, and the heading and the body of the bill are then written. The bill may consist of a single item or any number of items, and when the bill is completed the operator notes upon the detachable stub of the bill 20 the number on the scale adjacent the last item on the bill or moves a suitable slide 26 along the scale to this line. The carrier is then moved until the starting arrow 25 points to the number on the scale which was indicated by the last item of the bill. The bill 25 is then torn off from the stub and a new blank bill secured in place. It will thus be noted that each bill may be made to follow directly after the last preceding bill irrespective of the length of the latter, and that the sales sheet or leaf of the sales book may be completely 30 filled. When one side of the latter has been filled the sheet is turned over, and by means of the openings in the detachable section 14, it is again secured in place and the opposite side of the sheet filled. If desired, a plurality of sheets may be placed upon the support 35 at the same time, there being two of these sheets illustrated in the drawings. To prevent the carbon sheet 23 from being soiled or rumpled while one bill is being removed and another one secured in place, I may, if desired, cover said carbon sheet with a thin sheet 27 of tissue paper of the same size as the carbon paper. The carbon sheet may be made of the same size as the bill, or if a longer bill is to be written, two carbon sheets may be used by securing one upon the two upper pins or studs 18 and one to the lower pins or studs 18. 40

45 No part of the carbon paper is exposed to soil the fingers or the sales sheet, and by securing the carbon paper to the bill carrier, no portion of the sales sheet is exposed to the influence of the carbon save that directly beneath the bill, and by means of the scale and arrows it is unnecessary to lift the carbon to inspect the sales sheet when a new bill is secured to the carrier. The last line upon which the last item is written is indicated by the scale, and in moving the starting line 50 25 to the proper number on the scale, there is no possibility of any space on the sales sheet being wasted or any of the bills overlapping.

Having thus described my invention, I claim as new and desire to secure by Letters Patent:

1. A device of the class described, comprising a suitable support, means along one edge thereof adapted to receive and retain a sales sheet, and a carrier slidably mounted adjacent the opposite edge of said support and having means adapted to receive and detachably retain a carbon sheet and a bill. 60

2. A device of the class described, comprising a suitable support, studs or pins adjacent one edge thereof adapted to receive and retain a sales sheet, and a carrier slidably mounted adjacent the opposite edge of said support and having studs or pins adapted to receive and detachably retain a carbon sheet and a bill. 65

3. A device of the class described, comprising a suitable support having a slideway with inwardly directed flanges adjacent one edge thereof, means adjacent the opposite edge adapted to receive and detachably retain a sales sheet, a carrier mounted within said slideway and frictionally engaging beneath said flanges, and studs or pins secured to said carrier and extending outwardly between said flanges and adapted to receive and detachably retain a carbon sheet and a bill. 70

4. A device of the class described, comprising a suitable support, means adjacent one edge thereof adapted to receive and detachably retain a sales sheet, a carrier slidably mounted adjacent the opposite edge of said support and having means adapted to receive and retain a carbon sheet and a bill, and a scale mounted on said support substantially parallel with said carrier. 80

5. A device of the class described, comprising a suitable support, means adjacent one edge thereof adapted to receive and detachably retain a sales sheet, a slideway adjacent the opposite edge of said support, and a carrier mounted in said slideway and adapted to receive and retain a carbon sheet and a bill, said support having a scale 90 thereon parallel with said slideway and adjacent said bill.

6. A device of the class described, comprising a suitable support, means adjacent one edge thereof adapted to receive and retain a sales sheet, a slideway adjacent the opposite side of said support and having inwardly directed flanges, a carrier within said slideway and frictionally engaging with the under side of said flanges, means on said carrier adapted to receive and detachably retain a carbon sheet 95 and a bill, and a bill having a detachable section marked to indicate the first line of the subject-matter entered upon the body of the bill, and said support having a scale adjacent the detachable section of the bill and adapted to co-operate therewith to determine the position of the bill 100 upon the sales sheet.

7. A device of the class described, comprising a suitable support, means adjacent one edge thereof adapted to receive and retain a sales sheet, a slideway adjacent the opposite side of said support and having inwardly directed flanges, 110 a carrier within said slideway and frictionally engaging with the under side of said flanges, means on said carrier adapted to receive and detachably retain a carbon sheet and a bill, and a bill having a detachable section marked to indicate the first and the last line of the subject-matter 115 entering upon the body of the bill, and said support having a scale adjacent the detachable section of the bill and adapted to co-operate therewith to determine the position of the bill upon the sales sheet.

In testimony whereof I have signed my name to this 120 specification in the presence of two subscribing witnesses.

WILLIAM ROBERT BOHMERT.
